UNITED STATES PATENT OFFICE.

FREDERICK KAHL, OF WEEHAWKEN, NEW JERSEY.

MEANS FOR HOLDING BED-SHEETS IN POSITION.

SPECIFICATION forming part of Letters Patent No. 739,682, dated September 22, 1903.

Application filed May 2, 1903. Serial No. 155,306. (No model.)

To all whom it may concern:

Be it known that I, FREDERICK KAHL, a subject of the Emperor of Germany, residing at Weehawken, in the county of Hudson and State of New Jersey, have invented certain new and useful Improvements in Means for Holding Bed-Sheets in Position, of which the following is a specification, such as will enable those skilled in the art to which it applies to make and use the same.

The object of this invention is to provide means for holding a bed-sheet in proper position on a mattress, so as to prevent the sheet from wrinkling or becoming twisted or otherwise getting out of position.

The invention is fully disclosed in the following specification, of which the accompanying drawings form a part, in which the separate parts of my improvement are designated by suitable reference characters in each of the views, and in which—

Figure 1 is a perspective view of a bed the sheet of which is provided with my improvement; and Fig. 2 a transverse section of the bed-frame, mattress, and sheet and showing my improvement.

In the drawings forming part of this specification I have shown in Fig. 1 an ordinary bedstead or frame, which comprises the usual end members *a* and *b*, side bars *c*, and transverse end bars *d*; but my invention is not limited in any way to the construction of a bedstead or frame. I have also shown at *e* an ordinary mattress and at *f* a sheet, which is placed thereover, and in practice I form in

the sides of the sheet, at the edge thereof, hem or pockets *f*², through which are passed rods *g*, and these rods are provided at their ends with holes *g*² and connected therewith are springs *h*, which are provided with hook members *h*², which are adapted to engage the bottom of the side bars *c* of the bedstead or frame.

The springs *h* hold the sheet *f* in proper position and stretched smoothly and evenly across the top of the mattress. It will be understood that the usual bed-coverings are placed over the sheet *f* in the ordinary manner, and the length of the springs *h* may be regulated so as to adapt the apparatus to any style of bed-frame or bedstead.

Having fully described my invention, what I claim as new, and desire to secure by Letters Patent, is—

A bed-sheet, the side edges of which are provided with longitudinal pockets, rods passed through said pockets, and springs connected with the ends of said rods and adapted to be connected with the side portions of the bedstead, substantially as shown and described.

In testimony that I claim the foregoing as my invention I have signed my name, in presence of the subscribing witnesses, this 1st day of May, 1903.

FREDERICK KAHL.
